UNITED STATES PATENT OFFICE.

WALTER F. STIMPSON, OF DETROIT, MICHIGAN.

DESIGN FOR A PEDESTAL FOR COFFEE-GRINDERS.

47,204.

Specification for Design.

Patented Apr. 6, 1915.

Application filed September 24, 1914. Serial No. 863,407. Term of patent 14 years.

To all whom it may concern:

Be it known that I, WALTER F. STIMPSON, a citizen of the United States of America, residing at Detroit, in the county of Wayne and State of Michigan, have invented a certain new, original, and ornamental Design for Pedestals for Coffee-Grinders, of which the following is a specification, reference being had therein to the accompanying drawings, forming part thereof.

The figure represents a perspective view of a pedestal as applied to a coffee grinder, showing my new design.

I claim:

The ornamental design for a pedestal for coffee grinders, substantially as shown.

WALTER F. STIMPSON.
